(57) **CLAIM**

The ornamental design for a combination ceiling fan and light fixture, as shown and described.

DESCRIPTION

FIG. 1 is a perspective view from below of a combination ceiling fan and light fixture in accordance with my design;

FIG. 2 is a reduced top plan view of the combination ceiling fan and light fixture in accordance with my design;

FIG. 3 is a reduced bottom plan view of the combination ceiling fan and light fixture in accordance with my design;

FIG. 4 is a front elevation view of the combination ceiling fan and light fixture in accordance with my design;

FIG. 5 is a back elevation view of the combination ceiling fan and light fixture in accordance with my design; and,

FIG. 6 is a side elevation view of the combination ceiling fan and light fixture in accordance with my design, the opposite view being a mirror image thereof.

The broken line showing of a portion of a light fixture is included for the purpose of illustrating environmental structure and forms no part of the claimed design.

1 Claim, 6 Drawing Sheets
